UNITED STATES PATENT OFFICE

171,525

CARRIAGE

Hans K. Bergmann, Grayslake, Ill.

Application May 18, 1953, Serial No. 25,098

Term of patent 14 years

(Cl. D14—14)

To all whom it may concern:

Be it known that I, Hans K. Bergmann, a citizen of the United States and a resident of Grayslake, in the county of Lake and State of Illinois, have invented a new, original, and ornamental Design for a Carriage, of which the following is a specification, reference being had to the accompanying drawing, forming a part thereof.

In the accompanying drawing:

Figure 1 is a side elevation view of a carriage embodying my new design.

Figure 2 is a fragmentary sectional view of the same device shown in Figure 1 and taken along the lines 2—2 of Figure 1 for convenience of illustration.

Figure 3 is an end elevation view of a carriage.

Figure 4 is a perspective view of a carriage.

I claim:

The ornamental design for a carriage, substantially as shown.

HANS K. BERGMANN.
